UNITED STATES PATENT OFFICE

122,943

DESIGN FOR A FAN CASING OR SIMILAR ARTICLE

Lurelle Guild, Darien, Conn.

Application February 13, 1940, Serial No. 90,231

Term of patent 14 years

To all whom it may concern:

Be it known that I, Lurelle Guild, a citizen of the United States of America, residing in Darien, Connecticut, have invented a new, original, and ornamental Design for a Fan Casing or Similar Article, of which the following is a specification, reference being had to the accompanying drawings, forming a part thereof and of which:

Fig. 1 is a side elevational view;

Fig. 2 is a front elevational view; and

Fig. 3 is a front perspective view of a fan casing showing my design.

I claim:

The ornamental design for a fan casing or similar article, as shown.

LURELLE GUILD.
